CLAIM

The ornamental design for a shoe, as shown and described.

DESCRIPTION

FIG. 1 is a top front perspective view of a shoe showing the claimed design;

FIG. 2 is an enlarged view of the area 2 encircled by dot-dot-dash lines in FIG. 1;

FIG. 3 is a top rear perspective view thereof; and,

FIG. 4 is a side view thereof.

The dashed broken lines in the figures show portions of the shoe that form no part of the claimed design.

The dot-dash broken lines in the figures show boundaries that form no part of the claimed design.

1 Claim, 4 Drawing Sheets---
